KITCHEN UTENSIL

Filed Sept. 17, 1928

UNITED STATES PATENT OFFICE

WILLIAM HODGES AND WALTER F. HODGES, OF PHILADELPHIA, PENNSYLVANIA, AS
SIGNORS TO WILLIAM HODGES & COMPANY, A PARTNERSHIP COMPOSED OF WIL-
LIAM HODGES AND WALTER F. HODGES, OF PHILADELPHIA, PENNSYLVANIA

KITCHEN UTENSIL

Application filed September 17, 1923. Serial No. 206,531.

This invention, generally stated, relates to a device for use in kitchens and has more especial relation to a so-called cream whip or beater.

5 The leading object of the present invention is to provide as a new article of manufacture a device which is of simple and inexpensive structure and compact in form for use in the kitchens of homes, hotels, restaurants, clubs, 10 and other places for the whipping or beating of cream, in which means is provided integral with the beater proper for containing a cooling agent as cracked ice or iced water for obtaining better results in the whipping of 15 cream.

A further object of the present invention is to provide a device of the character stated in which is provided a stand having companion or twin compartments mounted thereon but separate from one another, of which one compartment is arranged to contain a cooling agent, as cracked ice or iced water, and of which the other compartment contains a rotary beater.

25 Other and further objects of the present invention consists in the provision of general details of construction and in the arrangement, connection, and combination of parts for attaining the results sought by the foregoing objects.

30 The invention consists of the novel construction hereinafter described and finally claimed.

The nature, characteristic features and 35 scope of the invention will be more fully understood from the following description taken in connection with the accompanying drawings forming part hereof, and in which:

Fig. 1, is a view in perspective of a cream 40 whip or beater embodying the invention.

Fig. 2, is a view taken upon the line 2—2 of Fig. 3.

Fig. 3 is a view taken upon the line 3—3 of Fig. 2.

45 For the purpose of illustrating this invention, one form thereof has been shown in the accompanying drawings which is at present preferred, since the same has been found in practice to give satisfactory and reliable results, although it is to be understood that the

various instrumentalities of which the invention consists can be variously arranged and organized and that the invention is not limited to the precise arrangement and organization of the instrumentalities as herein shown and described. 55

Referring to the drawings in detail, the reference numeral 1 designates a support, and, as shown, consists of a pair of legs 2 of metal each formed in one piece and bent cross-wise in arched fashion and then upwardly, as shown in Fig. 2, to provide a substantially U-shaped support. This structure provides a very light and inexpensive supporting stand and the free ends 3, which are 60 the upper ends, are arranged to engage around the lower convexed surface 4 of a casing 5. This lower convexed surface 4 of the casing 5 is also arranged to rest upon the arched portions 6 of each leg 2. The legs may be 65 secured to the casing in any desired way, as by solder. The casing 5 is usually made of metal and is provided with a pair of adjoining or twin compartments designated 7 and 8. These compartments are separated one from 70 the other by means of an imperforate vertical wall or partition designated by the reference numeral 9. In practice compartment 7 is 75 made smaller than is compartment 8, and is adapted to contain a cooling agent as cracked ice or iced water; and compartment 8 is arranged to contain the whipper or beater. Compartment 7 is provided with the flat end 80

10 which is vertically disposed and is in parallelism with partition 9. Partition 9, 85 however, extends above the end 10 of compartment 7, as clearly shown in Figs. 1 and 3. This extension of partition 9 is designated 11 in Fig. 3. Fixed to extension 11 is a horizontally arranged strip 12, and having hinged 90 relation as at 13 with the strip 12 is a lid or cover 14, provided with downwardly extended flanges 15. These flanges 15 are adapted cooperatively to engage over certain of the upper edges of the casing 5 in order to prevent atmospheric air from reaching the interior of compartment 7. The hinged cover may be moved to abut against the extension 11 to retain the cover in open position for filling compartment 7 with a cooling agent. 100

The larger of the compartments, or that designated 8, is internally provided with a whipper or beater consisting of a plurality of radially arranged wires 16 bent U-shape and carried by end pieces 17. The end pieces 17 in turn are fixed to a horizontally arranged shaft 18 mounted for rotation between partition 9 and the vertical end wall 19 of casing 5. The end pieces 7 may be of any particular form, but in the present instance are shaped somewhat like a cross, and the arms of the cross-shaped members carry the bent-over ends of the wires 16. In order to prevent seepage of the contents of both compartments, members 20, rounded upon one side and flat upon the other, are fixed to partition 9 and the end piece 19 of casing 5. These members 20 may be soldered or otherwise affixed, as desired, and the member upon partition 9 is apertured to accommodate shaft 18. In order to prevent endwise movement of the beater and at the same time to guard against seepage, the arms 17 are provided with annular flanges 21 which abut against the partition 9 and the end piece 19 in alignment with the members 20. The shaft 18 is provided with a handle 22. The upper edge of extension 11, the end piece 19, and the two side walls of compartment 8 are in the form of a bead 23, preferably reinforced by a wire. Arranged to close compartment 8 is a lid or cover 24, preferably formed of metal and bent over to provide the pendant flanged part 25 which engages the inner walls of compartment 8. The lid or cover 24 is provided with a handle 26, and the casing 5 as a whole is provided with a pair of handles 27, shown as being riveted as at 28 to the casing 5.

The above described article provides a unitary structure in which cream may be whipped efficiently since the ice or iced water in compartment 7 cools sufficiently the contents of compartment 8 to give good cream whipping results.

We are aware that the invention may be embodied in other specific forms without departing from the spirit or essential attributes thereof, and we therefore desire the present embodiment to be considered in all respects as illustrative and not restrictive, reference being had to the appended claim rather than to the foregoing description to indicate the scope of the invention.

Having thus described our invention, what we claim as new, and desire to secure by Letters Patent, is:

A device of the character stated, comprising a support consisting of spaced legs curved at their tops to receive a casing and having an arched, convex portion between said legs, a casing having a pair of horizontally arranged adjoining compartments of which one is of less height and smaller than the other, said compartments having a continuous, convexly curved under surface common to both,

and each compartment having a substantially flat, vertical, outer end wall, said casing being mounted upon said legs with the said convexly curved undersurface of said casing resting upon the arched convex portions of said legs, an imperforate vertical partition arranged between said compartments in parallelism with said substantially flat ends, and extended above the top of said smaller compartment, the smaller compartment being unobstructed and arranged to contain a cooling agent, and the larger compartment being arranged to contain a commodity to be whipped, a horizontally disposed beater within the larger of said compartments, said beater having a shaft horizontally supported by said vertical partition and the outer flat end wall of said larger compartment, a cover removably fitted to the top of the larger compartment, and a cover hinged to the top of the smaller compartment, which hinged cover may be moved to abut against said imperforate partition to retain said cover in open position for filling the smaller compartment with a cooling agent.

WILLIAM HODGES.
